Specification for Design.

Patented Oct. 21, 1913.

Application filed August 21, 1913. Serial No. 786,038. Term of patent 7 years.

To all whom it may concern:

Be it known that we, REUBEN B. DISBROW and CARL M. CARLSON, both citizens of the United States, residing at Owatonna, in the county of Steele and State of Minnesota, have invented a new, original, and ornamental Design for Churn-Frames, of which the following is a specification, reference being had to the accompanying drawing, forming part thereof.

Figure 1 is a side elevation of a churn

frame, showing our new design; and Fig. 2 is an edge elevation of the same.

We claim:

The ornamental design for a churn frame, as shown.
